UNITED STATES PATENT OFFICE.

RICHARD J. FREEMAN, OF YOAKUM, TEXAS, ASSIGNOR OF ONE-HALF TO ALEX MAY,
JR., OF YOAKUM, TEXAS.

DOOR OPERATING AND LOCKING MEANS.

1,212,043.

Specification of Letters Patent.

Patented Jan. 9, 1917.

Application filed July 28, 1916. Serial No. 111,891.

To all whom it may concern:

Be it known that I, RICHARD J. FREEMAN, a subject of Great Britain, residing at Yoakum, in the county of Lavaca and State 5 of Texas, have invented new and useful Improvements in Door Operating and Locking Means, of which the following is a specification.

This invention relates to an improved 10 means for operating sliding doors, whereby the door may be moved to lock in any desired position.

A further object of the invention is to provide an actuating and locking means for 15 sliding doors including a rack that is connected to one of the edges of the door and which is actuated by a toothed wheel that cooperates with a plurality of other toothed wheels, the hub of one of the toothed 20 wheels having arranged thereon a disk provided with a spring pressed handle having its head formed with teeth which are adapted to co-engage with teeth upon a circular rack, and means being provided for locking 25 the handle when in engagement with the teeth of the circular rack to prevent the longitudinal movement of the rack bar and consequent movement of the door, means being also provided for sustaining the 30 handle at a right angle with relation to the disk to hold the said handle in operative position, and the teeth thereof out of engagement with the teeth of the circular rack, whereby to permit of the actuation of 35 the toothed wheels and the sliding movement of the door.

With the above and other objects in view the improvement resides in the construction, 40 combination and arrangement of parts set forth in the following specification and falling within the scope of the appended claims.

In the drawings: Figure 1 is an elevation illustrating my improvement upon the side of a car and showing the rack bar connected 45 with the sliding door for the car, Fig. 2 is a greatly enlarged sectional view approximately on the line 2-2 of Fig. 1, Fig. 3 is a similar enlarged sectional view approximately on the line 3-3 of Fig. 1, Fig. 4 is a sectional view approximately on the line 4-4 of Fig. 1, Fig. 5 is a detail view looking toward the outer face of the supporting or bed plate with the protective casing for the gears removed as is also the toothed 50 wheel having its hub provided with a disk,

Fig. 6 is a plan view of the underface of the disk, Fig. 7 is a sectional view illustrating the manner of retaining the handle in its open position, and Fig. 8 is a plan view of the disk, the lug and the end of the handle 60 engaging with the lug being shown in section.

While in the drawings I have illustrated the improvement in applied position upon the side of the car to operate the door therefor, it is to be understood that the improvement is not to be thus restricted in its useful capacity as the same may be employed with efficiency upon other devices having sliding doors.

In the drawings, the numeral 1 designates the side of an ordinary freight car, and 2 the door therefor. My improvement contemplates the employment of a base or bed plate 3 which is secured in any desired manner to the side of the car 1. Secured to the plate 3, at a suitable distance from the lower edge thereof is a circular toothed rack 4, the same being substantially in the nature of a ring member whereby an axle 5 secured 70 to the base or bed plate may extend centrally through the rack 4. Arranged for rotation upon this axle is the hub 6 of a toothed wheel 7, and secured to or formed with the outer end of the hub 6 is a flat disk 75 8 of a size to cover the circular rack 4, and this disk may be provided with an annular 80 depending flange 9 arranged around the circular tooth rack 4.

The disk 8 adjacent the peripheral edge 90 thereof is provided with a substantially rectangular opening 10 and with a centrally disposed groove 11 which intersects the opening, the said groove 11 adjacent the end thereof opposite the opening being centrally provided with a lug 12 having one or more transverse openings 13. The operating handle is indicated by the numeral 14 and includes an enlarged end in the nature of a head 15 which is disposed in the opening 10 and which is pivotally secured to the side walls provided by the said opening, as indicated by the numeral 16. The outer end of the head 15, at the portion thereof through which the pivot 16 passes, is centrally bifurcated, whereby a spring 17 may be coiled around the central portion of the pivot to exert a pressure or tension between the disk and the head 15 of the handle to normally swing the handle to within the 110

groove 11. The handle, adjacent the free end thereof, is provided with a rectangular slot 18 to receive the lugs 12, and the sides of the handle are provided with transverse openings 19, corresponding in number with the number of openings in the lug 12, and these alining openings are adapted to receive a seal or lock, whereby the handle cannot be swung to operative position to receive the disk by unauthorized persons. The inner face of the head 15 is provided with projecting teeth 20, and these teeth are adapted to intermesh with the teeth of the circular rack 4 to lock the disk upon the said circular rack, whereby to prevent the rotation of the disk and the rotation of the toothed wheel 7. To sustain the handle in its operative position, against the pressure of the spring 17, I provide a spring pressed bolt member 21 upon the outer face of the head of the said handle, which bolt is adapted to be received within a keeper 22 let into the disk 8.

The toothed wheel 7 meshes with a larger toothed wheel 23 that projects through an opening in the side or flange of the circular rack 4, the said toothed wheel 23 having secured to its inner face a small toothed wheel 24, both of the said wheels being journaled upon a suitable shaft or axle 25 that is secured to the base or bed plate 3.

The toothed wheel 24 engages with the teeth of a rack bar 26, one end of the said rack bar being provided with a bracket 27 that is connected to the door 2, while the opposite end of the rack bar is provided with a saddle or yoke member 28, antifrictional roller members 29 being journaled in bearings between the side members of the yoke 28. These rollers 29 engage with the opposite edges of a longitudinally extending guide rail 30 that has its opposite ends provided with angular portions forming feet that are secured to the side of the car 1.

It is, of course, to be understood that the rack bar is of a sufficient length to permit of the door being moved to its full open position when the disk is actuated to rotate the toothed wheels and move the rack bar longitudinally of the car, and also that the guide rail is of a sufficient length to permit of such movement of the door, while the yoke contacting with what may be termed the outer guide rail will serve to limit the movement of the door when the same has reached its full open position, and it is to be also understood that the door is provided with a suitable track or hanger whereby the same can be slid longitudinally of the door-way with the least amount of friction, and it is thought that the foregoing description, when taken in connection with the drawings, fully explains the invention and the operation thereof.

It is to be understood that the mechanism

is housed to protect the same from the elements, and as it is desirable that the handle member be closed after the operation of the device thereby it will be apparent that the employment of the spring pressed bolt 70 21 is arbitrary and that the said bolt may be discarded if desired.

Having thus described the invention, what I claim is:

1. In an operating and locking means for 75 the purpose set forth, a rack, a guide rail for the rack, a plurality of toothed wheels, one meshing with the rack, another of said toothed wheels having a hub provided with a disk, a circular rack disposed below the 80 disk, and a pivoted handle upon the disk having a head provided with teeth which normally engage with the teeth of the circular rack, and means for locking the handle upon the disk. 85

2. In a device for the purpose set forth, a movable rack bar, a guide rail for the rack bar, a plurality of intermeshing tooth wheels, one of which engages with the rack bar, another of said toothed wheels having 90 its hub provided with a disk, a circular rack disposed inward of the disk, a spring pressed handle member pivotally secured to the disk, said handle member including a head having teeth projecting through an 95 opening in the disk engaging with the teeth in the circular rack, a slotted lug upon the disk, said handle having an opening to receive the lug, the side of the handle having openings 100 communicating with the slots in the lug, as and for the purpose set forth.

3. In a device for the purpose set forth, a rack bar, a guide rail for the rack bar, a plurality of intermeshing tooth wheels, one of which engages with the rack bar, another of said toothed wheels having its hub provided with a disk, a circular rack disposed inward of the disk, a spring pressed handle member pivotally secured to the disk, said handle member including a head having 105 teeth projecting through an opening in the disk engaging with the teeth in the circular rack, a slotted lug upon the disk, said handle having an opening to receive the lug, the side of the handle having openings 110 communicating with the slots in the lug, and means upon the handle and co-operating with the disk for retaining the handle at a right angle with respect to the disk and the teeth thereof out of engagement with the 115 teeth of the circular rack. 120

4. In a device for the purpose set forth, a rack bar, said rack bar having its end provided with a yoke and anti-frictional rollers in the yoke engaging with the guide 125 rail, a peripherally toothed circular member journaled upon a shaft to one side of the rack bar, a hub having a toothed wheel also journaled upon the shaft, a disk upon the hub covering the toothed circular mem- 130

ber, a spring pressed handle upon the disk normally resting upon the outer face of said disk, a slotted lug upon the disk, said handle having a notch to receive the lug and having its sides provided with openings registering with the slots in the lug, said handle having an enlarged end comprising a head member which is pivotally secured to the disk and which has one of its faces 5 provided with teeth which normally engage with the teeth of the circular member, spring means for normally sustaining the

handle against the disk and the teeth thereof in engagement with the teeth of the circular member, a sliding lock upon the head 15 of the handle, a keeper upon the disk to receive the said lock, and whereby the handle is retained at a right angle with relation to the disk, and a plurality of intermeshing toothed wheels one of which engages with 20 the teeth of the rack bar.

In testimony whereof I affix my signature.

RICHARD J. FREEMAN.
